UNITED STATES PATENT OFFICE.

CHARLES A. LAPWORTH, OF WEST BRIDGEWATER, MASSACHUSETTS, ASSIGNOR OF ONE-HALF TO CHARLES E. MACLEOD, OF EASTON, MASSACHUSETTS.

FLAG-FLYING DEVICE.

Application filed September 9, 1924, Serial No. 736,694. Renewed January 21, 1928.

This invention relates to improvements in flag flying devices and the object thereof is to provide a simple and convenient means for supporting the flying flag in an auditorium, hall, room or any place in which there is not a sufficient current of air to maintain the flag in a flying position.

A further object of the invention is to provide a convenient device of this character 10 in which the flying flag can be controlled at will, so that, for example, during a band concert, upon the striking up of the National Anthem, the flag can be instantly broken out.

A further object of the invention is to provide a flag flying device of the character described with means for automatically illuminating the flying flag.

Another object of the invention is to provide a novel means for securing the flag to 20 the staff.

A further object of the invention is to provide an electrically controlled flying flag device which can be easily transported and readily set up in any desirable place.

25 Other objects and features of the invention will more fully appear from the following description and the accompanying drawings and will be particularly pointed out in the claims.

30 The preferred embodiment in the invention is illustrated in the accompanying drawings, in which,

Fig. 1 is an elevation of a flag flying device with flag flying;

35 Fig. 2 is a detail vertical sectional view of the upper portion of the tubular flag staff and translucent closure comprising a globe with an eagle mounted thereon, and means for illuminating the globe and eagle;

40 Fig. 3 is a detail view of a preferred form of deflector for projecting the jet of air from the chamber of the flag staff in a direction substantially normal to the axis of the flag staff;

45 Fig. 4 is a transverse sectional view through the flag staff showing an eye secured to said flag staff for supporting the end of the flag;

50 Fig. 5 is a detail view of the upper corner portion of the flag and a detachable resilient mean secured thereto for fastening the flag to the staff;

Fig. 6 is a similar view of a modified fastening means.

A preferred embodiment of the invention

which is illustrated in the accompanying drawings comprises a chambered flag staff 1 of any suitable height having means adjacent to the upper end of the flag staff for projecting a current of air or preferably a 60 plurality of jets of air from the chamber of said flag staff in a direction substantially normal thereof upon the flag.

In the particular construction illustrated, the flag staff 1 is provided with eyes 2 which are secured to the wall of the flag staff in any suitable manner, and suitable means are provided for securing the end of the flag to these eyes. A preferred means which is illustrated in Fig. 5 comprises a resilient member such as a helical spring 3 which has at its lower end a looped extension 4 which is stitched or otherwise secured to the flag and which has secured to its upper end a snap hook 5 adapted to be detachably connected to eyelet 2. A similar device may be secured to the lower corner of the flag or similarly securing such lower corner to the lower eye 2. By reason of this construction the end of the flag will be held taut and in substantial 70 alignment with the axis of the flag staff.

The flag staff is provided with a vertical series of ports 6 adapted to project jets of air against the flag and thereby to cause the flag to fly.

Deflectors desirably are provided for directing the jets horizontally from the flag staff and also for the purpose of increasing the strength of the jet over that of the current which would flow from a port unprovided with deflectors. Any suitable type of deflectors extending well into the chamber of the flag staff may be provided, a preferred form of deflector however is illustrated in Fig. 3 which comprises a tubular member 7 fitting the port in the wall of the flag staff and having a substantially semi-cylindrical extension 8 projecting well into the chamber of the flag staff. The deflector may be enclosed within the flag staff as illustrated or if desired may project a suitable distance beyond the outside of the wall of the flag staff.

Any suitable means may be provided supplying air under pressure to the chamber of 105 the flag staff. In the construction illustrated, the means for thus supplying air to the flag staff comprises a rotary blower having substantial cylindrical casing 9 with a fan 10 rotatably mounted therein and actu- 111

- ated by an electric motor 11, the shaft of which is integral with the shaft of the blower or suitably geared thereto. The combined motor and blower may be provided with a base 12 of such weight to properly support the flag staff and a suitable electric switch 13 may be provided for turning on and off the current to the motor and the illuminating device hereinafter to be described.
- 10 The blower casing is provided with an extension 14 from which the air from the fan is delivered. The extension desirably comprises a boss 15 having a screw threaded socket to receive and support the lower end 15 of the flag staff 1. The air of the blower is delivered directly to the chamber of the flag staff and the air is projected from the chamber of the flag staff through the ports 6 against the flag. The upper end of the flag 20 staff may be provided with any suitable closure to prevent the escape of air.
- One of the features of the present invention consists in providing a translucent closure for the upper end of the flag staff 25 provided with an illuminating device which will project rays of light upon the flying flag. In the particular construction illustrated herein the closure comprises a translucent globe 16 having at its lower end an enlarged boss 17 which encloses the upper end of the flag staff and is suitably secured thereto. Extending upwardly from the said globe and integral therewith is a figure 18 of an eagle also formed of translucent material and which may be colored to simulate the feathers of the eagle. The globe and eagle desirably are formed of glass and one or both may be ground or etched in the usual manner.
- 40 An electric light bulb 19 is supported within the translucent globe 16 upon a suitable cross head 20 in the upper end of the flag staff and suitable conductors 21 lead from the electric bulb downwardly through 45 the chamber of the flag staff to the switch 13 which controls the blower.
- In the operation of the device the blower with the flag staff and flag supported thereby may be placed in a suitable location in 50 the hall in which the flag is to be displayed. When it is desired to display the flag the switch 13 may be turned on to cause the motor to actuate the flag whereupon the air under pressure forced by the blower into 55 the chamber of the flag staff will discharge jets through the ports 6 against the flag causing it instantly to float out into position substantially normal to the axis of the flag staff; the intermittent action of the 60 vanes of the blower will cause the flag to flutter as in a strong breeze. By reason of the fact that the electric light 19 is also actuated from the same source of energy and controlled by the same switch as that which 65 actuates the blower, the flag will be in-
- stantly illuminated as it is broken out, thus a startling and pleasing effect is obtained. A flag flying device thus constructed is easily portable and can be readily installed in auditoriums, churches, clubs and various 70 places where patriotic meetings are held.
- In Figure 6 a modified form of means for supporting a flag is illustrated which comprises a cord 22 which is preferably secured within a hem 23 in the edge of the flag, the 75 ends of the cord being secured to snap hooks 24 which are adapted to be detachably connected to eyelets 2 as above described.
- The flag staff may be of any suitable length or form, and the chamber in the flag 80 staff may if desired extend only through an upper portion of the staff, suitable means being provided to supply the chamber with compressed air or means for projecting the jets of air upon the flag may be made independently of the flag staff secured thereto in proper position to project jets of air upon the flag as above described within the spirit and scope of the invention.
- It will therefore be understood that the 90 particular embodiment of the invention disclosed herein is of an illustrated character and is not restricted, and that various changes and construction, design and arrangement of parts may be made within 95 the spirit and the scope of the following claims.
- Having thus described my invention, what I claim as new, and desire to secure by Letters Patent, is:
1. A flag flying device comprising a longitudinally chambered staff having a series of vertically aligned circular ports in the wall thereof adjacent to the upper end of the staff, means for introducing air under 105 pressure into the chamber of said staff, cylindrical members in said ports having substantially semi-cylindrical portions extending inwardly from the walls of said ports presenting their concave faces in the path of the air current and acting to direct jets of air laterally from said staff in a direction substantially perpendicular to the axis of the staff and means for securing the end of the flag adjacent to said staff in substantial alinement with said ports.
2. A flag flying device comprising a longitudinally chambered staff having a series of vertically aligned ports in the wall thereof adjacent to the upper end of the staff, means 115 for introducing air under pressure into the chamber of said staff, means for securing an end of said flag adjacent to and in substantial alinement with said ports including a resilient member acting to hold the secured end of the flag taut and in substantial alinement with said ports.
3. A flag flying device comprising a longitudinally chambered staff having a series of vertically aligned ports in the wall there- 130

- of adjacent to the upper end of the staff, means for introducing air under pressure into the chamber of said staff, means for securing an end of said flag adjacent to and in substantial alinement with said ports including a resilient member secured to said flag and a snap hook connected to said resilient member adapted to be detachably connected with an eye upon said staff.
4. A flag flying device comprising an electric motor-driven blower forming a base, a tubular flag staff mounted upon said blower to receive the air projected from said blower and provided with a series of vertically aligned delivery ports adjacent to the upper end of said staff, a closure for the upper end of said staff comprising a hollow transparent globe with a communicating hollow transparent eagle mounted thereon, an electric light within said globe, an electric conducting means extending from said light downwardly through said staff, to the source of electric energy which actuates said blower, and means for securing an end of the flag to said staff in substantial parallelism with said ports.
5. A flag flying device comprising an electric motor-driven blower forming a base, a tubular flag staff mounted upon said blower to receive the air projected from said blower and provided with a series of vertically aligned delivery ports adjacent to the upper end of said staff, a closure for the upper end of said staff comprising a hollow transparent globe with a communicating hollow transparent eagle mounted thereon, an electric light within said globe, an electric conducting means extending from said light downwardly through said staff, to the source of electric energy which actuates said blower, and means for securing an end of the flag to said staff in substantial parallelism with said ports.
6. A flag flying device comprising an electric motor-driven blower forming a base, a tubular flag staff mounted upon said blower to receive the air projected from said blower and provided with a series of vertically aligned delivery ports adjacent to the upper end of said staff, a closure for the upper end of said staff comprising a hollow translucent device forming a closure for the upper end of said staff, an electric light therein, an electric conducting means extending from said light downwardly through said staff to the source of electrical energy which actuates the said blower, and means for securing the said blower, and means for securing

In testimony whereof, I have signed my name to this specification.

CHARLES A. LAPWORTH.
